UNITED STATES PATENT OFFICE.

JOHN W. O'DANIEL, OF CLOVERDALE, INDIANA.

DOOR-SPRING.

SPECIFICATION forming part of Letters Patent No. 369,203, dated August 30, 1887.

Application filed June 27, 1887. Serial No. 242,696. (No model.)

To all whom it may concern:

Be it known that I, JOHN W. O'DANIEL, of Cloverdale, in the county of Putnam and State of Indiana, have invented certain new and useful Improvements in Door-Springs; and I do hereby declare the following to be a full, clear, and exact description of the invention, such as will enable others skilled in the art to which it pertains to make and use it, reference being had to the accompanying drawings, which form part of this specification.

My invention relates to an improvement in door and gate closers; and it consists in the combination, with a stationary plate and a plate which is secured to the door, of two rods which have their outer ends loosely connected to the two plates and their inner ends made to pass through a spiral spring and attached to opposite ends of the spring, and the spring, the two plates having a series of perforations, all of which will be more fully described hereinafter.

The object of my invention is to provide a device for keeping doors or gates closed which is simple in construction, which can be applied to gates and doors of all kinds without any change whatever, and which can be easily and quickly adjusted to any desired tension, according as it is applied to heavy or light doors or gates.

Figure 1 is a perspective of my invention applied to a door. Fig. 2 is a detail view of one of the rods.

A represents the frame of the door, and B the door. The perforated plate C is preferably secured to the top of the frame A by means of screws, as shown, and the perforated plate D to the door near its upper edge. The two rods E E have their outer ends bent at right angles, as shown at F, and their inner ends bifurcated, as at G.

Passing around the inner ends of the two rods E E is the spiral spring H, which has its ends placed in the bifurcated ends of the rods E E, and the two rods are made sufficiently long to pass by each other and through the spiral spring, as shown.

When the door is opened, the inner ends of the two rods are forced outward and the spring extended, and when the door is released the tension of the spring draws the inner ends of the two rods E E toward each other, thus causing the door or gate to close. The plates C D, being provided with a series of perforations, it is only necessary to lift the bent end of one of the rods E out of the perforations in the plates, when the tension of the spring can be increased or decreased at will.

The above construction produces a closer which can be readily attached to or detached from doors and gates of all kinds, and at any point thereon, as convenience may dictate.

Having thus described my invention, I claim—

In a door or gate closer, the combination, with the stationary perforated plate C and the perforated plate D, which is secured to the door, of the two rods E and spring H, the outer ends of the rods being bent at right angles and secured to the plates, and their inner ends passing through the spring and secured to opposite ends thereof, substantially as shown and described.

In testimony whereof I affix my signature in presence of two witnesses.

JOHN W. O'DANIEL.
